UNITED STATES PATENT OFFICE.

FRITZ HOLLSTEIN, OF HAWTHORNE, NEW JERSEY, ASSIGNOR TO JOHN GROSSGEBAUER,
OF PATERSON, NEW JERSEY.

REED FOR LOOMS.

Application filed September 3, 1927. Serial No. 217,320.

In weaving certain materials, as artificial silk or rayon and certain cheaper grades of silk or the like, it is necessary to employ a relatively coarse reed with a plurality of such warp threads in each space between adjacent dents, and it is well known that such practice produces a coarse appearing finished product. Before the time when artificial silk or rayon were used to any great extent, attempts have been made in the weaving of fine silk fabrics to lessen the breakage of silk threads contained in a very fine reed, having a very small pitch, by providing a reed with strands of thread or wire placed in front of and forming a permanent part of said reed, such strands arranged to alternate with the dents of the reed at the instant of beating in by the lay, with the warp threads passing in groups between such strands, but crossed or divided relatively to the grouping in the reed dents, the combined effect being that of a finer reed at the moment of beating in. These attempts have failed in practice, because of the fact that the loom structure had to be altered at considerable expense and inconvenience in order to accommodate the device, or because of the fact that the entering and tieing of the silk threads became too cumbersome and expensive. Other efforts, to lessen the breakage of silk threads, when contained in fine pitch reeds, have been made by using reeds having curved dents and double reeds. These efforts have failed because of the fact that the dents could not bend in such a manner as to allow the threads to move unimpededly at the bends or because the exact position of the warp threads at the moment of beating up was not assured.

A primary object of my invention is to provide a separately formed independent auxiliary reed adapted to serve with the main reed without requiring mechanical changes in the loom structure and consequently easily applied to the usual lay with the additional advantage of the silk threads being readily entered and tied by reason of its independence of the main reed.

The invention consists in certain novel features of construction and arrangement by which the above objects are attained, to be hereinafter described and claimed.

The accompanying drawings form a part of this specification and show the invention, as applied to a ribbon loom of a usual type,

only so much of the lay being shown as is necessary in illustrating the relation of the main and auxiliary reeds thereto.

Figure 1 is a plan view showing a portion of the lay with the reeds mounted thereon. 60

Figure 2 is a corresponding front elevation showing the shuttle-races, with the shuttles omitted.

Figure 3 is a vertical section taken on the line 3—3 in Figure 2. 65

Figure 4 is a vertical section corresponding to a portion of Figure 3, showing in dotted lines the relation of the main reed and the auxiliary or fore-reed at the instant of beating in. 70

Figure 5 is a face view of the main reed.

Figure 6 is a similar view of the fore reed.

Figures 7 and 8 are diagrammatic horizontal sections showing the relation of the dents of the main reed and fore-reed before 75 and at the instant of beating in, respectively, and the positions of the warp threads in both conditions.

Similar reference numerals indicate the same parts in all the figures. 80

The lay 10 may be understood to be in all respects as usual in construction, equipment and operation, having the race-blocks 11 and race-ways 12, in which the shuttles, not shown, are traversed by the usual mechanism, 85 also omitted.

The blocks 11 are secured to vertical studs 13 joined at their upper ends to a transverse bar 14 extending longitudinally of the lay. The usual rabbet 15 at the back of the lay, 90 together with a bar 16 similar to the bar 14, forms a groove for the reception of the lower margins of the reeds.

The vertical margins of the reeds are received in the pockets or spaces 17 between the blocks 11 and bars 14 and 16, and the reeds are loosely held against lateral movement by the wedges or filling-pieces 18. Vertical movement is resisted by an adjustable stop 19, bolted to the bar 14, which allows the reeds 100 a degree of vertical movement while preventing escape from the groove 15, thus permitting the slight movement of the reeds required by the warp-threads in their passage therethrough. 105

The main reeds are as usual, having bands 20 at the top and bottom and end bars 21 at each side with a series of dents 22 extending between the bands. The dents are thin strips of steel equally spaced and held rigidly. 110

- The auxiliary or fore-reeds comprise each a series of dents 23 received in bands or holders 24 at the top and bottom with no end bars, and are preferably cylindrical in cross section. Thus constructed the fore-reeds are flexible transversely, and are mounted each in front of its corresponding main reed with the dents 22 of the main reed separated from the dents 23 of the fore reed by a space determined by the thickness of the bands 20 and holders 24, as clearly shown in Figures 3 and 4, and both reeds are mounted on the lay and held loosely in place thereon as above described.
- 15 The warp ends are reeded as illustrated in Figures 7 and 8; assuming four warp threads to traverse the space between each adjacent pair of dents 22 of the main reed, the same number traverse the space between each 20 adjacent pair of dents 23 of the fore reed but the latter four are made up of the third and fourth threads of one main reed group with the first and second of the next main reed group, so that at the instant of beating up the 25 dents 22 and 23 assume momentarily the position shown in Figure 8, in which the reed spaces of the combined reeds carry each two warp threads only; and thus their proper position in the fabric is assured and the appearance 30 of the finished product improved.

The dents of the fore reed correspond in pitch to those of the main reed and their elasticity insures their immediate return to the original positions on the backward movement of the lay.

35 As the main and fore reeds are entirely independent the reeding of each is easily and economically performed, and as both are

mounted on the lay in the usual manner, no changes in the loom structure are necessary. 40

Although the invention is shown and described as applied to a ribbon loom, it will be understood that it will serve in weaving broad fabrics and with other types of looms using various materials as the warps. 45

I claim:—

1. In a loom, a main reed, having immovable dents, in combination with a fore reed separate from and bodily movable in relation thereto and formed independently of 50 said main reed and having horizontally flexible dents permanently spaced in fixed relation and corresponding in pitch to said immovable dents, and means for mounting said reeds upon the lay in spaced relation to each other, with said fore reed in front of said main reed.

2. In a loom, a main reed having immovable dents, in combination with a fore reed 60 separate from and formed independently of and bodily movable in relation thereto said main reed and consisting of a top band and a bottom band only, with a series of dents of elastic flexible wire extended between said bands, said series of flexible dents 65 permanently spaced and supported in predetermined fixed relation and adapted to bend on lines parallel with said bands, such flexible dents corresponding in pitch to said immovable dents, and means for mounting 70 said reeds upon the lay in spaced relation to each other, with said fore reed in front of said main reed.

In testimony that I claim the invention above set forth I affix my signature hereto.

FRITZ HOLLSTEIN.
